UNITED STATES PATENT OFFICE.

LAWRENCE STARR, OF SOUTH WILLIAMSPORT, PENNSYLVANIA.

NECKTIE-STIFFENER.

1,358,400.

Specification of Letters Patent. Patented Nov. 9, 1920.

Application filed March 10, 1920. Serial No. 364,846.

To all whom it may concern:

Be it known that I, LAWRENCE STARR, a citizen of the United States, residing at South Williamsport, in the county of Lycoming and State of Pennsylvania, have invented certain new and useful Improvements in Necktie-Stiffeners, of which the following is a specification.

This invention relates to a necktie stiffener 10 and has for its object to provide an open ended necktie of the four-in-hand type with a device which will cause it to retain its shape under all conditions of service and thereby prolong its life and usefulness.

For a full understanding of my invention, 15 reference should be had to the accompanying description and drawing: wherein—

Figure 1 is a fragmentary plan view of a necktie having its facing broken away to 20 show the stiffener inserted therein, and

Fig. 2 is a section taken on the line 2—2 of Fig. 1 looking in the direction of the arrows.

By referring to the drawing by numerals 25 it will be seen that 1 designates a four-in-hand tie of ordinary construction having the usual opening end and having the fabric folded so as to form a facing 2 and the usual flaps 3 which overlap each other. The stiffener consists of the upper transverse rod 4 and the lower transverse rod 5, the rod 5 being slightly larger in length than the rod 30 4. The ends of the transverse rods 4 and 5 are connected by the rods 6 thus forming a 35 frame which tapers toward its upper end.

The lower transverse rod 5 is provided with an enlarged portion 7 which is semi-circular in shape. A spring clip 8 is attached upon the lower edge of the transverse rod 5 so that 40 the coil spring 9 will normally force the jaw 10 against the enlarged portion 7.

From the above description it will be 45 readily understood that this stiffener is inserted in the open end of an ordinary four-in-hand tie as is clearly shown in Fig. 1. After the stiffener has been inserted in the tie it will be seen that the clip 8 will be open so as to allow the flaps 3 to be securely held between the jaw 10 and the enlarged portion 7 50 thereby securely holding the stiffener within the open end of the tie. This stiffener it will be seen will not only cause the tie to retain its desirable shape but will also prevent the tie from sliding out of the vest or 55 coat as is usual in ties of this description. Because of the construction of the frame of the stiffener and also the provision of the clip

8 it will be seen that the stiffener may be inserted and removed from the open end of the tie with very little trouble to the wearer of 60 the tie.

The above description refers to what I call the preferred form of my invention but I wish it understood that I may make such changes in construction, arrangement, and 65 combination of parts as will fall within the scope of the appended claims.

Having thus described my invention what I claim as new is:

1. A device of the class described comprising an upper transverse rod and a lower transverse rod, rods connecting the ends of said transverse rods, and an enlargement formed on the lower transverse rod intermediate its ends, and means provided upon 75 said enlargement for holding said device within a tie.

2. As a new article of manufacture, a tie 80 stiffener comprising an upper and a lower transverse rod, said transverse rods being situated parallel to each other, said upper transverse rod being shorter than said lower transverse rod, rods connecting the ends of said transverse rods thus forming a tapering frame, an enlargement formed on the lower 85 transverse rod intermediate its ends, and means provided on said enlargement for holding said stiffener within the open end of a tie.

3. As a new article of manufacture, a tie 90 stiffener comprising an upper and a lower transverse rod, said transverse rods being parallel to each other, and said upper transverse rod being shorter than said lower transverse rod, rods connecting the ends of said transverse rods thereby forming a tapered frame, and an enlargement formed on said lower transverse rod intermediate its ends, a spring clip mounted upon said enlarged 95 portion of said lower transverse rod for holding said stiffener within the open end of a tie for the purpose specified.

4. A device of the class described comprising a pair of parallel transverse rods, rods connecting the ends of said transverse rods, and mean for attaching one of said transverse rods to the edges of a tie within the open end thereof.

In testimony whereof I affix my signature in presence of two witnesses.

LAWRENCE STARR.
